(57) **CLAIM**

The ornamental design for a burner bump-out, as shown and described.

DESCRIPTION

FIG. 1 is a first top perspective view of a burner bump out showing our new design.

FIG. 2 is second top perspective view thereof rotated 90 degrees from FIG. 1.

FIG. 3 is a first bottom perspective view thereof.

FIG. 4 is a second bottom perspective view thereof rotated 90 degrees from FIG. 3.

FIG. 5 is a top plan view thereof.

FIG. 6 is a bottom plan view thereof.

FIG. 7 is a first elevation view thereof.

FIG. 8 is a second elevation view thereof.

FIG. 9 is a third side elevation thereof, opposite the first side.

FIG. 10 is a fourth side elevation thereof, opposite the second side.

FIG. 11 is a cross-section view thereof taken through section line 11-11 as shown in FIG. 5; and,

FIG. 12 is a cross-section view thereof taken through section line 12-12 as shown in FIG. 5.

The broken lines in the figures depict the bounds of the claimed design and unclaimed subject matter, which forms no part of the claimed design.

All surfaces not shown form no part of the claimed design.

1 Claim, 12 Drawing Sheets
